Bartlett & Brewster

UNITED STATES PATENT OFFICE.

JAMES F. GOGGIN, OF GARFIELD, NEW JERSEY.

COMBINED OUTLET-BOX AND FIXTURE.

1,237,501.

Specification of Letters Patent. Patented Aug. 21, 1917.

Application filed July 28, 1916. Serial No. 111,775.

To all whom it may concern:

Be it known that I, JAMES F. GOGGIN, a citizen of the United States, residing at Garfield, county of Bergen, State of New Jersey, have invented certain new and useful Improvements in Combined Outlet-Boxes and Fixtures, of which the following is a full, clear, and exact description.

My invention relates to improvements in combined outlet boxes and fixtures and has for its object to provide a means for supporting a fixture on an outlet box whereby parts now commonly used are dispensed with and the number of parts used is reduced.

The following is a description of an embodiment of my invention, reference being had to the accompanying drawings, in which—

20 Figure 1 shows a vertical section of an embodiment of my invention.

Fig. 2 is a bottom view of the cover with part of the insulating flange broken away.

Fig. 3 shows a section of a modification.

25 Fig. 4 shows a side elevation of the insert of said modification.

Referring more particularly to the drawings, 1 is an outlet box of ordinary form having lugs 2 and ordinary knock-out holes 3 and secured to a beam by screws 4. Such boxes heretofore have been provided with studs carrying insulating connectors on which "hickey's" are screwed, the fixture being screw-threaded to the outer end of the 30 "hickey." In order to do away with the necessity of the studs, connectors and "hickey's" I provide a plate 5 having a metallic insert 6 surrounded by molded insulating material 7 which extends to the edge of the box and is there provided with elongated holes 8, through which extend screws 8' engaging the lugs 2 and holding the plate to the box so as to form a cover therefor. The insert is provided with a screw-threaded 45 hole 9 which is tapered so as to be slightly larger at its outer end. In one form the insert is provided with lateral projections 10 and elongated lateral extensions 11 which prevent the insert from turning relatively to the molded insulation. The projections 11 are provided at their ends with recesses which form projections 12 embracing the holes 8 but separated therefrom so that no portion of the insert is in metallic contact 55 with the screws 8' passing through the holes 8. These extensions 11 reinforce the mold-

ed insulation across the center and at the points 8 where the holding screws 8' pass through.

Into the tapped hole 9 is screwed the 35 threaded pipe 13 of a fixture through which pass electric conductors 14 entering the outlet box through the knock-out holes 8.

From the foregoing it will be seen that the fixture is secured to the outlet box by 40 the use of a single composite member and is thereby insulated from the outlet box so as to meet underwriters' requirements.

Figs. 3 and 4 show a modification in which 6' is an insert formed with two end flanges 15, the body being provided with radial ridges 16. The body of the insert is embedded in insulation molded upon the insert under pressure, the ridges 16 acting 45 as anchors to prevent relative rotation.

While various kinds of insulation may be used for the insulation surrounding the insert, I prefer to use what is known in the trade as gummon, the same being a very hard, strong, waterproof and fireproof insulation of high dielectric strength.

As will be evident to those skilled in the art my invention permits of various modifications without departing from the spirit thereof or the scope of the appended claims.

What I claim is:

1. The combination of an outlet-box-body, a cover composed of a metallic portion having a centrally located tapped hole and a laterally extending rim comprising insulating material insulating said metallic portion from said box-body, and securing means passing through said rim and engaging said box-body so as to secure said cover thereto, said metallic portion having a lateral extension 90 embedded in said insulating material and spaced apart from said securing means.

2. The combination of an outlet-box-body, a cover composed of a metallic portion having a centrally located tapped hole and a laterally extending rim comprising insulating material insulating said metallic portion from said box-body, and securing means passing through said rim and engaging said box-body, said metallic portion having radial projections embedded in said insulating material and spaced apart from said securing means.

3. The combination of an outlet-box-body, a cover composed of a metallic portion having a centrally located tapped hole and a laterally extending rim comprising insulat-

ing material insulating said metallic portion from said box-body, and screws passing through said rim and engaging said box-body, said metallic portion having extensions embedded in said insulating material embracing said screws but spaced apart therefrom.

4. The combination of an outlet-box-body, a cover composed of a metallic portion having a centrally located tapped hole and a laterally extending rim comprising insulat-

ing material insulating said metallic portion from said box-body, and securing means passing through said rim and engaging said box-body, the face portion of said 15 rim extending beyond the periphery of its rear portion and the wall of said box, said metallic portion having a lateral extension embedded in said insulating material and spaced apart from said securing means.

JAMES F. GOGGIN.
